CONTRACTING MANDREL

John G. O'Neil, Faribault, and Lawrence G. Zesbaugh, Minneapolis, Minn.; said Zesbaugh assignor to said O'Neil

Application October 24, 1940, Serial No. 362,558

7 Claims. (Cl. 242—72)

This invention relates to a mandrel or a supporting member upon which flexible material may be wound and while said mandrel may have various applications, it particularly is designed for use in the formation of a container made from flexible material.

It is an object of this invention to provide a mandrel or supporting member upon which flexible material such as paper may be wound and which is constructed and arranged to be moved so that the diameter of its periphery is reduced to facilitate the removal of the material wound thereon.

It is a further object of the invention to provide a mandrel comprising a plurality of segments forming a substantially continuous periphery but having longitudinal spaces therebetween and means whereby the diameter of said periphery may be reduced by a longitudinal movement of said segments.

It is another object of the invention to provide such a mandrel as above set forth in which the said segments are held in normal position by resilient means.

It is also an object of the invention to provide a mandrel of simple and efficient construction which can be readily attached to and detached from a carrying spindle, which mandrel may have either a cylindrical or polygonal periphery which may be readily reduced in diameter so that the material on the mandrel may be easily removed.

These and other objects and advantages of the invention will be fully set forth in the following description made in connection with the accompanying drawings in which like reference characters refer to similar parts throughout the several views and in which—

Fig. 1 is a central longitudinal section through the mandrel showing a portion of the carrying means;

Fig. 2 is a view in end elevation as seen from line 2—2 of Fig. 1 looking in the direction of the arrows;

Fig. 3 is a vertical section taken on line 3—3 of Fig. 1 as indicated by the arrows;

Fig. 4 is a vertical section taken on line 4—4 of Fig. 1 as indicated by the arrows;

Fig. 5 is a vertical section taken on line 5—5 of Fig. 1 as indicated by the arrows;

Fig. 6 is a central longitudinal section through a removing sleeve;

Fig. 7 is a view in end elevation as seen from the right of Fig. 6; and

Figs. 8, 9 and 10 are partial views similar to

Fig. 1 illustrating the position of the material on the mandrel and the removal thereof by the sleeve shown in Fig. 6.

Referring to the drawings, a mandrel or supporting member is shown comprising a central carrying member or core 20. While this member might take various forms, in the embodiment of the invention illustrated it is shown as a cylindrical shell having one end firmly secured to and mounted on a plug 21. Plug 21 is shown as reduced in diameter to receive shell 20 and provided with a shoulder against which the end of shell 20 engages. Plug 21 is interiorly bored and threaded to receive or have screwed thereinto the threaded end 22a of a carrying spindle 22. Spindle 22 is shown as having a supporting member 23 carried in a turret 24, a portion only of which is shown. Plug 21 is exteriorly threaded and a supporting member 25 is interiorly threaded to be mounted on plug 21. Member 25 can thus be moved longitudinally of member 21 by being rotated thereon. A locking nut 25c is threaded in member 25 and engages member 21, the same having slots 25d at its inner side adapted to receive a tool for turning the same. Member 25 has a periphery 25a which is tapered or which has a tapered or frusto-conical surface. A plurality of segments 26 are provided, the end portions 26a of which are bent outwardly slightly and are supported upon the tapered surface 25a. The segments 26 are constructed and arranged to form a substantially continuous periphery but are spaced longitudinally. While the number of segments may be varied, in the embodiment of the invention illustrated three of such segments 26 are shown and these have longitudinal edges which are slightly spaced as shown in Figs. 4 and 5. The other ends of segments 26 have portions 26b which are offset inwardly a short distance. These end portions 26b are supported upon the periphery of a supporting member or collar 27 interiorly threaded to be screwed on the threaded periphery of shell 20. Said member 27 has a periphery which is tapered or of frusto-conical form and this periphery tapers in the same direction as surface 25a of member 25. Member 25 is provided with a threaded portion 25b and a holding sleeve 28 has its end interiorly threaded to be screwed on member 25. Sleeve 28 has a lip or flange 28a extending inwardly and which engages the segments 26 for holding the same on the supporting member 25. A ring 29 is mounted on the end of shell 20 and has a flaring or frusto-conical end 29a, the interior of which has a frusto-conical

surface and engages the offset portions 26b of segments 26, thus holding the same on member 27. Ring 29 is shown as engaging the outer end of the threaded portion of shell 20 and said shell is slightly expanded or spun over the outer end of ring 28 to hold the same securely thereon. A collar 30 is also threaded on shell 20 and engages one end of the supporting member 27, collar 30 being provided with slots 30a by means of which it can be turned. Collar 30 forms in effect a jamb or lock nut for member 27. A compression coiled spring 31 surrounds shell 20, bearing at one end against collar 30 and bearing at its other end against a collar or washer 32 which in turn engages cylindrical members or studs 33 projecting inwardly from segments 26 respectively by having reduced portions riveted in said segments.

In Fig. 6 a shell or sleeve 36 is shown and the same has formed therein a plurality of circumferentially spaced slits or kerfs 36a which extend throughout the greater portion of the length of member 36. Member 36 is slightly flared at one end 36b.

In operation, the mandrel is brought into the proper position by movement of turret 24 and it has wound thereon one or more layers of material 38. In practice this material has been a heavy glazed paper and a plurality of layers have been wound on the mandrel. After the paper has thus been wound on the mandrel it is severed and glued so that there is a shell formed which tightly embraces the mandrel. While the container shell might be removed in various ways, in practice the sleeve 36 has been used. This sleeve will have thereon a circular band 37 of resilient material so disposed as to give the desired tension on the portions between the kerfs 36a. The material of the member 36 is, of course, resilient. The member 36 is carried on a suitable carrier and at the proper time is moved longitudinally over the container shell 33. It is arranged to fit the shell tightly and to be moved thereover with some friction. It will thus have considerable grip on the shell and when it is moved outwardly toward the end of the mandrel it grips container shell 33 which is, of course, tightly gripping the segments 26. Container shell 33 is moved outwardly and it moves with it the segments 26. This longitudinal movement of segments 26 causes the end portions thereof to move downwardly or inwardly along the tapered surfaces of members 25 and 27 and the diameter of the periphery formed by segments 26 is thus reduced. The segments come substantially into contact and due to the reduced diameter of said periphery container shell 33 is released from the segments and moves freely off of the mandrel with member 36. The movement of segments 26 takes place against the pressure of spring 31 which is slightly compressed in this action. Spring 31 acts to hold the sleeves 26 in their normal position. The periphery of the mandrel is thus easily and quickly reduced as the container shell wound thereon is removed. As soon as the shell is removed spring 31 moves segments 26 back to their normal position and the mandrel is ready to have another container shell wound thereon.

From the above description it will be seen that we have provided a very simple and efficient mandrel and one especially useful in the making of a container from flexible material. The parts of the mandrel are easily made and assembled and it can be very accurately adjusted. It

is arranged so that it can be quickly placed on and removed from its supporting spindle. The device has been amply demonstrated in actual practice and found to be very successful and efficient.

It will, of course, be understood that various changes may be made in the form, details, arrangement and proportions of the parts, without departing from the scope of applicants' invention, which generally stated, consists in a device capable of carrying out the objects above set forth, in the parts and combinations of parts disclosed and defined in the appended claims.

What is claimed is:

1. A collapsible mandrel having a substantially continuous periphery adapted to have a sheet of flexible material wound thereon and comprising a plurality of slightly longitudinally separated segments, a central core, spaced supporting means for and disposed at the ends of said segments mounted on and relatively adjustable on said core, said supporting means having conical surfaces tapered in the same direction and resilient means surrounding said core holding said segments in position on said supporting means whereby said segments may be moved longitudinally and will move on said tapered surfaces to reduce the diameter of the periphery thereof.

2. A collapsible mandrel having in combination, a pair of spaced supporting members, said members having conical surfaces both tapering in diameter in the same direction, a member on which said supporting members are carried, a plurality of segments having their end portions carried on said tapering surfaces, said segments having comparatively small thickness and forming a substantially continuous periphery but being slightly separated longitudinally, annular members overlying the ends of said segments for retaining them on said supporting members and resilient means between said supporting members normally holding said segments in position whereby said segments may be moved against the pressure of said resilient means and move on said tapering surfaces to reduce the diameter of the periphery thereof.

3. A collapsible mandrel comprising a central member adapted to be attached to a carrying spindle and comprising a cylindrical plug and tubular core carried thereby, spaced supporting members movably mounted upon said plug and core respectively, the same having peripheries tapering in the same direction, a plurality of segments of thin material having their end portions supported upon said tapering surfaces, spaced from said core and having spaced longitudinal edges, said segments forming a periphery adapted to have a flexible sheet wound thereon, members overlying the ends of said segments for holding the same on said supporting members and resilient means surrounding and supported on said core between said supporting members acting on said segments normally holding the same in longitudinal position whereby said segments may be moved longitudinally against the pressure of said resilient means to move on said tapered surfaces to reduce the diameter of the periphery thereof.

4. A collapsible mandrel having in combination, a central carrying member having an end portion adapted to be attached to a spindle and a core carried by and projecting from said end portion, spaced supporting members mounted on said end member and core respectively, the same having peripheral surfaces tapering in the same

direction, a plurality of longitudinally spaced segments having their end portions carried on said tapered surfaces and spaced from said core, rings for holding said end portions on said peripheries, a spring surrounding and supported on said core, means on said carrying member against which one end of said spring engages and means carried by said segments acted on by the other end of said spring whereby said spring acts to hold said segments in normal position and said segments may be moved longitudinally to move on said tapered peripheries and reduce the diameter of the periphery thereof.

5. A collapsible mandrel having in combination, a core member adapted to be attached to a supporting spindle, conical members at the ends of said core member having their surfaces tapering in the same direction, a shell of comparatively thin material formed of a plurality of slightly spaced longitudinally divided segments supported at their ends on said conical surfaces, a coil spring surrounding said core between said supporting members and members at the inner sides of said segments acted on by said spring to move said segments longitudinally.

6. A collapsible mandrel having in combination, a central member, supporting members at the ends of said central member having conical surfaces, said surfaces tapering in the same direction, a shell formed of slightly spaced longitudinally divided segments supported at their ends on said conical surfaces and spaced from said central member, rings surrounding the ends of said segments respectively for holding the same on said surfaces, members secured to the inner sides of said segments and disposed between the same and said central member, a spring surrounding said central member and actuating on said last mentioned members to move said segments longitudinally on said surfaces, one of said supporting members being threaded on said central member for longitudinal adjustment thereon.

7. The structure set forth in claim 6, a lock member for said last mentioned supporting member threaded on said central member, said spring having one end engaging said lock member.
